UNITED STATES PATENT OFFICE.

THOMAS KERWIN AND JOHN McGINLEY, OF PHILADELPHIA, PENNSYLVANIA, ASSIGNORS TO FRIEDBERGER MANUFACTURING COMPANY, OF PHILADELPHIA, PENNSYLVANIA, A CORPORATION OF PENNSYLVANIA.

DESIGN FOR TRIMMING FOR LADIES' UNDERWEAR.

SPECIFICATION forming part of Design No. 36,895, dated April 26, 1904.

Application filed March 22, 1904. Serial No. 199,482. Term of patent 3½ years.

To all whom it may concern:

Be it known that we, THOMAS KERWIN and JOHN McGINLEY, citizens of the United States, residing at Philadelphia, county of Philadelphia, and State of Pennsylvania, have invented a new, original, and ornamental Design for Trimming for Ladies' Underwear, reference being had to the accompanying drawing for an illustration of the same.

10 The figure represents a plan view of the trimming.

What we claim is—

The ornamental design for trimming for ladies' underwear, as shown.

THOMAS KERWIN.
JOHN McGINLEY.
